UNITED STATES PATENT OFFICE

127,994

DESIGN FOR AN OVERSHOE OR SIMILAR WATERPROOF ARTICLE

John E. Hard, Cranston, R. I., assignor to Goodyear Footwear Corporation, Providence, R. I., a corporation of Delaware

Application May 9, 1941, Serial No. 100,867

Term of patent 14 years

To all whom it may concern:

Be it known that I, John E. Hard, a citizen of the United States, residing at Cranston, in the county of Providence and State of Rhode Island, have invented a new, original, and ornamental Design for an Overshoe or Similar Waterproof Article, of which the following is a specification, reference being had to the accompanying drawing, forming part thereof.

I claim:

The ornamental design for an overshoe or similar waterproof article, substantially as shown.

JOHN E. HARD.
